UNITED STATES PATENT OFFICE.

WILLIAM McINTOSH, OF WILMINGTON, ILLINOIS.

HORSESHOE-CONFORMATOR.

No. 839,181.

Specification of Letters Patent.

Patented Dec. 25, 1906.

Application filed April 9, 1906. Serial No. 310,650.

To all whom it may concern:

Be it known that I, WILLIAM McINTOSH, a citizen of the United States, residing at Wilmington, in the county of Will and State of Illinois, have invented certain new and useful Improvements in Horseshoe-Conformators, of which the following is a specification.

My invention is an improved horseshoe-conformator made of iron, aluminium, or other fireproof material.

The object is to save the horseshoer much fatigue and waste of time in ascertaining the size of shoe needed for the horse being shod, such as having to lift the horse's foot several times to try the shoe being shaped and walking back and forth several times from forge to horse.

After the horse's hoof is prepared for adjusting a shoe to it my device can be placed on the hoof and adjusted to the size of shoe needed, and the shoer can then take the measure or pattern to the forge and get the proper sized and shaped shoe by adjusting the same to the pattern, and thus save much time and fatigue.

My device is in four sections spliced together, and held in place by bolts and thumb-screws.

The ends of the lapping parts are sufficiently curved to allow the sections to hinge with each other just enough to permit the pattern to be expanded or contracted to the size of any hoof. Place for heel end can be

marked, as the pattern is designed for the longest as well as shortest shoes.

The curve of the pattern will be perfectly regular for the average-sized shoe. Otherwise there will be a slight departure from a regular curve, but not enough to prevent the pattern being an accurate guide to the shaping of the shoe.

In the drawings, Figure 1 is a top view of my device, and Fig. 2 is a view showing how sections are spliced together, with heads of bolts A embedded, leaving a smooth bottom surface, and thumb-screws B to loosen or tighten the joints when adjusting the pattern to any required size.

What I claim as my invention, and desire to secure by Letters Patent, is—

A horseshoe-conformator of four sections, the sections being joined by the ends being spliced and fitted together in the form of sockets and held together by means of thumb-screws, so that the conformator can be adjusted to any desired size by lessening the thumb-screw pressure at the joints and then made rigid by increasing the thumb-screw pressure at the joints, substantially as described and illustrated.

In testimony whereof I affix my signature in presence of two witnesses.

WILLIAM McINTOSH.
